V. A. LEACH,
COIN RECEIVING AND DELIVERING DEVICE,
APPLICATION FILED OCT. 22, 1919.

1,391,840.

Patented Sept. 27, 1921.

UNITED STATES PATENT OFFICE.

VIVIAN A. LEACH, OF SAN FRANCISCO, CALIFORNIA.

COIN RECEIVING AND DELIVERING DEVICE.

1,391,840.

Specification of Letters Patent. Patented Sept. 27, 1921.

Application filed October 22, 1919. Serial No. 332,846.

To all whom it may concern:

Be it known that I, VIVIAN A. LEACH, a citizen of the United States, residing in the city and county of San Francisco and State of California, have invented a certain new and useful Improvement in a Coin Receiving and Delivering Device, of which the following is a specification.

My invention relates to improvements in coin receiving and delivering devices wherein a gravity operated device operates in conjunction with a delivering chute to retain coins within said chute until actuated by the hand of an operator.

The primary object of the present invention is to provide improved means for delivering coins or change.

A further object of the invention is to provide improved means for exposing the amount of change or coins delivered to the recipient of said coins in order that he may determine the amount thereof.

A still further object of the invention is to provide an improved and simplified construction having a maximum efficiency whereby the delivery of change or coins may be facilitated.

I accomplish these several features by means of the preferred form of the invention disclosed in the drawings forming a part of the present specification wherein like characters of reference are used to designate similar parts throughout the said specification and drawings, and in which:

Figure 1 is a broken plan view of my improved device as applied to the edge of a shelf or the like;

Fig. 2 is a broken side elevation, partly in section, of Fig. 1; and

Fig. 3 is a vertical sectional view taken on line 3—3 of Fig. 2 in the direction indicated.

Referring to the drawings the numeral 1 is used to designate an inclined chute having upwardly extending sides 2 and an open top. The upper end of the chute 1 is provided with an extension 3 by means of which said upper end may be attached to the front edge of a shelf 4 or the like with the bottom of said chute 1 lying flush with said shelf 4.

To provide sufficient rigidity to the chute 1 a strut or brace 6 is provided which extends from the lower end of the chute 1 to the under side of the shelf 4 as disclosed in Fig. 1 of the drawings.

The bottom of the chute 1 is offset along a median line as at 7, said offset diminishing toward the upper end of the chute 1. This novel feature is provided to prevent the binding of two adjacent coins sliding down said chute in lateral relation. In such a case one coin will be lifted or raised above and overlap the other.

At the lower end of the chute 1 is mounted a housing 8 having an open top and bottom and an orifice 9 arranged to permit the passage of coins from the lower end of the chute 1 into said housing. The housing 8 is likewise provided with a plurality of inwardly turned lugs 11 arranged to slidably engage slots 12 within a gravity operated housing 14 slidably mounted within the first mentioned housing 8 and likewise provided with an orifice 16 adapted to register with the orifice 9 of the housing 8 when said housing 14 is raised, against the action of gravity, by the hand of an operator or the recipient of the coins to be delivered, and thereby permit the passage of coins from the chute 1, through the orifice 9 of the housing 8 and into the second gravity operated housing 14 and thus into the hand of the operator or recipient.

The open tops of the chute 1 and housing 8 are covered with a transparent element 17 to expose the number and denomination of the coins, or the amount of the change, to the recipient, before operation of the delivering mechanism.

In operation the change or coin to be delivered is placed in the upper end of the chute 1 and precipitated by gravity to the lower end thereof, any laterally adjacent coins being elevated one above the other by the offset portion 7 of the chute 1 as hereinbefore described.

The normal position of the gravity operated housing 8 will operate to close the orifice 9 and thereby prevent the passage of coins from the chute 1 until the said housing 8 is raised by the operator placing his hand under the bottom of the said housing 8 and raising the same until the orifice 16 therein registers with the orifice 9 in the housing 8 and at the lower end of the chute 1. This registration of the orifices 9 and 16 will permit the passage of the coins from the chute 1 and into the hand of the operator.

Upon removal of the hand of the operator the gravity actuated housing 14 will be returned to normal position to close the ori-

fice 9 and thereby prevent the passage of the next collection of coins until the device is operated by the next or successive recipient.

Having thus described my invention what 5 I claim as new and desire to secure by Letters Patent is:

1. As an article of manufacture, a coin receiving and delivering device comprising an inclined chute adapted for engagement to 10 the edge of a shelf or the like for receiving coins; a housing mounted upon the lower end of the chute having an orifice connecting the interior of the housing with the chute; an inner housing slidably mounted within 15 the first mentioned housing, and having an orifice adapted to register with the first mentioned orifice when said inner housing is raised, said inner housing being open at both ends thereof and provided with a plurality 20 of longitudinally disposed slots in the sides thereof; inwardly turned lugs formed upon

the bottom of the outer housing, and adapted to engage the slots in the inner housing for limiting the downward movement of said inner housing, whereby the housing offices are normally retained in a non-registered relation. 25

2. As an article of manufacture a coin receiving and delivering device comprising an inclined chute adapted at the upper end 30 thereof for engagement with a shelf or the like, said chute being offset longitudinally along a median line whereby coins on either side of said line may be held in different planes to prevent binding of said coins within the chute; a housing mounted upon the lower end of the chute and having an orifice for the passage of coins from said chute to 35 said housing.

In witness whereof I hereunto set my sig 40 nature.

VIVIAN A. LEACH.
